SHAVING IMPLEMENT

Ivar Jepson, Chicago, Ill., assignor to Chicago
Flexible Shaft Company, Chicago, Ill., a corpo-
ration of Illinois

Application May 21, 1938, Serial No. 209,235

3 Claims. (CL 30—43)

This invention relates to shaving implements of the type known as dry shavers and has for its object certain improvements on the invention in the patent to John Bruecker, No. 2,081,694.

5 One of the objects of the present invention is to provide a shaving implement of the character described in which the perforated portion of the comb is slowly oscillated or moved back and forth while the cutter is in operation. The movement 10 thus imparted to the comb supplements the motion imparted by the hand of the operator in moving the shaving head across the face and this supplemental movement serves to more effectively work the beard hairs into the small openings and thus enhance the efficiency of the shaver.

Another object is to provide an improved structure and operating means for simultaneously operating the cutter and the comb for the purpose 15 intended.

Other objects and attendant advantages will be appreciated by those skilled in the art as the invention becomes better understood by reference to the following description when considered in 20 connection with the accompanying drawing, in which—

Figure 1 is a longitudinal sectional view through the cutting head end of a shaving implement embodying my invention;

30 Fig. 2 is a face view of the comb, removed;

Figs. 3 and 4 are cross-sections taken substantially on the section lines 3—3 and 4—4 of Fig. 1; and

Figs. 5 and 6 are enlarged cross-sections 35 through the cutting head showing the opposite positions of the comb.

My invention contemplates slowly moving a curved or tubular comb back and forth upon and with respect to the housing or handle proper by 40 means of which the comb is manipulated in the shaving operation and this movement of the comb being simultaneous with the operation of a cutter in cooperation with the inner side of the comb. In the form here shown, the comb designated 45 generally by 11 is tubular and has a closely perforated portion 12 adapted to be moved over the face for reception of the beard hairs. The comb is mounted at one end upon a hub 13 which in turn is mounted to turn upon and about a sleeve 14. This sleeve in turn is journaled in a bearing 15 in a housing or body structure designated generally by 16. Within the sleeve 16 is journaled a shaft 17 which projects beyond both ends of the sleeve. Upon one end of the shaft 17 is 50 fixed a gear 18 which is driven by a gear 19 in

turn fixed to a power driven shaft 21 journaled in the body structure above mentioned. This shaft 21 may be the armature shaft of an electric motor housed in the body structure. The motor is preferably of such small size and the body structure is so shaped and proportioned as to be held in the hand of the operator for manipulating the shaving implement. Upon the opposite end of the shaft 17 is mounted a cutter holder designated generally by 22 equipped with one or more cutter blades of any suitable or preferred construction adapted to be moved across the inner side of the perforated portion of the comb in shearing engagement therewith. In the present case I have shown flat cutter blades 23 of the type and construction described in my copending application Serial No. 209,233 filed May 21, 1938. These blades are free to move radially and in the cutting operation each blade is pressed outwardly against the inner side of the perforated portion of the comb by centrifugal force which may, if desired, be supplemented by the pressure of a light flat spring 24. In the embodiment here shown the cutter blades are rapidly moved across the curved perforated portion of the comb in 55 shearing coaction therewith by rotation of the head 22 driven from the armature shaft 21 as above described. Simultaneously with this operation of the cutter blades the comb 11 is slowly oscillated by suitable means, such, for example, as a driving train operated from the armature shaft 21. As an illustration the shaft 21 has an extension 25 which is connected through suitable intermediate reduction gearing 26 and 27 to an eccentric operating shaft 28 journaled in what may 60 be termed the gear casing portion 29 of the housing structure. To this shaft 28 is fixed an eccentric 31 which operates a connecting rod or link 32 pivotally connected at 33 to the comb-carrying hub 13. The arrangement is such that upon each complete rotation of the shaft 28 and its eccentric 31 the tubular comb will be oscillated back and forth from the position shown in Fig. 5 to the position shown in Fig. 6 and back to the starting position shown in Fig. 5. As a further 65 illustration referring to Fig. 3, it will be noted that the arc designated 34 represents approximately 68° on the face of the comb which in this instance is the approximate width of the perforated area. The comb will be oscillated approximately 68° in a counterclockwise direction viewing Fig. 3 to the position denoted by the arc 35, and then back again to the original position. This back and forth movement of the comb is performed simultaneously with the oper- 70

- ation of the cutter and does not disturb the co-operative relation between the cutter and the comb. The relative speed of the cutter blades with respect to the comb as well as the relative speed of the comb with respect to its supporting body may, of course, be varied, the intention being that the comb shall be moved slowly back and forth at approximately 100 complete oscillations per minute, or less than this rate.
- 10 The invention is not to be understood as restricted to the details set forth, since these may be modified within the scope of the appended claims, without departing from the spirit and scope of the invention.
- 15 I claim:
1. In a shaving implement, in combination, a comb of cylindrical configuration having a shaving area of extremely thin material provided with closely positioned hair receiving openings, a cutter adapted to move across the inner side of said shaving area in shearing engagement with the inner edges of said openings, a holder for the

cutter mounted to move about an axis coaxial with the longitudinal axis of said cylindrical comb, means for operating the holder to move the cutter at a high rate of movement in said shearing engagement, and means operating simultaneously with the cutter operating means to oscillate the comb about said longitudinal axis at a slow rate of movement compared with said movement of the cutter.

2. A shaving implement as set forth in claim 1, in which the hair receiving openings are arranged in an elongated area parallel with said longitudinal axis and the comb oscillations are of amplitude sufficient to move the shaving area back and forth a distance approximating the width of said area.

3. A shaving implement as set forth in claim 1, in which the cutter holder is mounted on a shaft adapted to be power driven for operating the cutter in the shearing engagement, and in which the comb is supported coaxially upon said shaft.

IVAR JEPSON.
